GRAFTING TOOL

William E. Rawlings, Santa Clara County,
Calif.

Application September 11, 1935, Serial No. 40,054

2 Claims. (Cl. 47—6)

In one method of grafting it is common practice to saw a limb off of a tree at a selected point and then saw a wedge-shaped piece out of the edge of the limb portion remaining, and fitting 5 a scion into the wedge-shaped opening thus made. In forming this wedge-shaped cut in the manner indicated the saw invariably leaves a cut with rough surfaces, and one that is fibrous and indefinite where the two sides join, with the 10 result that in order to provide a perfect job other finishing tools must be used.

It is also true that in the above indicated method it is frequently difficult to form a cut as desired because of the difficulty in handling the 15 saw in awkward positions.

It is, therefore, an object of the present invention to provide a tool so constructed and arranged that the desired operation may be performed quickly and smoothly in one operation 20 or movement, and that may be readily applied to a limb portion in any position.

It is also an object to provide a tool of the character indicated so constructed and arranged that one portion may be readily applied as a 25 chisel.

It is also an object of the invention to provide a tool of the character indicated that will be economical to manufacture, simple in form and construction, strong, durable, and highly efficient 30 in its practical application.

In the drawing:

Figure 1 is a side elevation of a tool embodying my invention.

Figure 2 is a view on line 2—2 of Figure 1. 35 In the particular embodiment of the invention herein disclosed I show at 1 a one-piece bar forming a handle portion 2 and having a part 3 disposed at an acute angle to the longitudinal axis of the handle portion 2 and thence curving 40 backwardly toward said axis as at 4. The part 4 forms a finger terminating at 5 to bear against the end of the cut limb, a portion of which is indicated in dotted lines at 6.

At 7 is shown another substantially straight 45 bar having a handle portion 8 and having a bifurcated end portion 9 adapted to receive the part 3 of bar 1.

The bars 1 and 7 are pivotally connected at 50 their point of intersection by means of a bolt as shown at 10, consequently the two bars have a relative swinging movement about the pivot 10 and in a common plane.

A spring 11 is inserted between the two handle 55 portions to normally urge them apart.

The cutting blade comprises a V shaped member 12 having parallel leg portions 13 which seat in sockets such as 14 in bifurcations 9 and bolted

to the bar 7 as at 15. The front end of the member 12 is sharpened to form a chisel edge at 16, and the two converging upper edges are also sharpened as at 17.

In using the tool the finger 4 is placed upon 5 the end of the freshly cut end of the limb with the point of the cutting member 12 in engagement with the side of the limb as shown. Now when the two handles are pressed together the bar 7 rotates about its fulcrum 10 and the cutting member is forced upwardly through the bark and wood and the desired segment of the tree is quickly and smoothly cut out and is removed by dropping away through the space between 10 the sides of the V shaped member 12 as at 18. 15

When the bar 7 is held in one fixed position the cut made by the point of member 12 will, of course, be arcuate in form because the said point moves in a circle about the fulcrum 10. But if so desired the cut may be straightened somewhat 20 during the cutting operation by elevating the handle 8 at the same time that the two handles are being pressed together, thereby moving the whole tool about the point 5.

Ordinarily the bar 1 will be held substantially 25 stationary when in use, any movement that it may have being upwardly and pivoting on point 5.

In this device the bar 1 functions as a support for the movable fulcrum 10 only, and does not 30 take any part in the actual cutting.

If it is desired to use the bar 7 as a chisel only for enlarging or shaping the cut the bolt 10 may be removed and the two bars separated. The bolts 15 may also be removed if desired and the part 12 detached from the bar 7 for convenience 35 in sharpening the cutting edges.

It is to be understood, of course, that while I have herein shown and described but one specific embodiment of the invention changes in 40 form, construction, and method of assembly and application may be made within the scope of the appended claims.

I claim:

1. A grafting tool comprising, a pair of fulcrumed arms, one arm terminating at one end in a finger adapted to bear against the end of the limb to be cut, and the other arm having its corresponding end terminating in a V shaped cutting blade with the cutting edges disposed in opposed relation to said finger but out of cutting relationship therewith. 45

2. The structure set forth in claim 1 in which the front or closed end of the V shaped blade is also provided with a cutting edge in angular relation to the V shaped cutting edges. 50

WILLIAM E. RAWLINGS. 55
